UNITED STATES PATENT OFFICE.

CARL G. PRITCHARD, OF WARREN, OHIO, ASSIGNOR TO THE HARRIS AUTOMATIC PRESS COMPANY, OF NILES, OHIO, A CORPORATION OF OHIO.

FEEDER.

1,242,978.

Specification of Letters Patent. Patented Oct. 16, 1917.

Application filed February 12, 1915. Serial No. 7,737.

To all whom it may concern:

Be it known that I, CARL G. PRITCHARD, of Warren, in the county of Trumbull and State of Ohio, have invented certain new and useful Improvements in Feeders; and I do hereby declare the following to be a full, clear, and exact description of the invention, such as will enable others skilled in the art to which it appertains to make and use the same.

In an application for patent filed by Walter H. Smith February 10, 1915, Serial No. 7282, provision is made for separating and feeding bag-tubes from a pile thereof by moving the topmost bag-tube longitudinally and then transversely, advantage being taken of the stiffness of the material (which is enhanced by the usual corrugations which extend longitudinally of bag-tubes) to permit the longitudinal movement to be effected by a pusher or separating element engaging one edge or end of the bag-tube. According to the particular means shown in such application each bag-tube is moved longitudinally from the pile, the initial movement of the pusher or separator being supplemented by a further longitudinal movement effected by take-out rolls, by which latter the articles are fed into the feeding-path of a printing press or other paper-handling machine. The bag-tubes are there received on a table from which they are fed transversely, or at right angles to their initial line of movement, into the machine. The arrangement referred to contemplates having the feeder and pile of bag-tubes offset relatively to the press at one end thereof, and this feature is open to the objection that a press so equipped requires considerable space, more in fact than is often feasible in a printing or like establishment.

According to my invention the pile may be located directly in front of the machine, and it is not necessary that the articles, after being separated by the initial longitudinal movement, be wholly removed from the pile before being moved transversely or at right-angles to the initial movement. By my invention it is only necessary to move the topmost article sufficiently to allow or cause a portion thereof to project beyond the edge of the pile, whereupon such projecting portion will be positively engaged by gripping means through the instrumentality of which

the article is then fed at right-angles to its initial movement.

The object of my present invention is to economize space, and to provide improved and highly efficient means for feeding bag-tubes and other articles forward from a pile thereof after being partly separated from such pile.

In the accompanying drawings, Figure 1 is an end elevation, the cylinders of a printing press being indicated in outline. Fig. 2 is a view at right-angles to Fig. 1. Fig. 3 is a plan view. Fig. 4 is a side elevation, partly in section, showing a slight modification. Fig. 5 is a view at right-angles to Fig. 4. Fig. 6 is a plan view of Fig. 5.

Referring to the drawings, 1 designates a pile of stock which I have shown as being composed of bag-tubes for handling which my invention is especially adapted, but its use is not restricted since it may be employed with equal facility for handling various articles. The means for supporting the pile and for maintaining it at a uniform level form no part of my present invention, and further reference thereto is unnecessary. While various means may be employed for moving the topmost article to cause it to project beyond the edge of the pile, I have shown for this purpose a pusher or separator 85 in the form of a hooked member 2 which is designed to reciprocate on the top of the pile, near one end, so as to hook into the notch at the end of the topmost bag-tube and move the latter longitudinally of the pile a sufficient distance to cause its opposite end to project beyond the edge of such pile. I have shown this member 2 as mounted on a reciprocating rod 3 which is actuated by a bell-crank 4 and a cam 5 engaging therewith, such engagement being insured by a spring 6.

Adjacent to that edge of the pile beyond which the topmost article is designed to be projected is an inclined guide 7 by means of which each article is guided into suitable gripping members for engaging the end of the article and then moving the latter at right-angles to its initial movement. I have shown a choke-gage 8 bearing downwardly on guide 7 to prevent the passage to the gripping members of more than one article at a time. Any suitable or known means may be employed for this purpose.

According to the means shown in Figs. 110

1 to 3 the gripping members by which the secondary movement is imparted to the stock comprise spaced-apart lower feed rolls 9 (positively driven by the gearing indicated in Figs. 2 and 3), and upper coöoperating feed rolls 10 which are raised and lowered by gears 12, rack 13, and cam 14, such upper feed-rolls being raised to permit the articles to enter between them and the lower rolls. 5
10 When the upper rolls are lowered the article is firmly held by the gripping members, and the rolls being spaced-apart will contact with the stock over a relatively wide surface, insuring thereby the feeding of the 15 stock from the pile at right-angles to its initial movement longitudinally of the pile. Each article is thus fed to the take-out rolls by which it is delivered to the press or other paper-handling machine. I have shown the 20 lower take-out roll 15 in the form of one continuous cylindrical body with which the upper take-out rolls 16 engage.

In proximity to that end of the pile beyond which the topmost article is designed 25 to project, I locate a knocker or jogger 19 which is shown in the form of a spring-held lever fulcrumed on one of the side frames and to which is connected a rod 20 with which engages an actuating cam 21. 30 While I prefer means such as I have above described for carrying out my invention, yet such means may be widely varied without departing from the spirit of my invention. Thus, in Figs. 4 to 6 I have shown 35 differently constructed gripping members for imparting the secondary movement to the stock, but such gripping members, like those before described, have an extended area of contact with the stock and effect the 40 movement of the latter at right angles to its initial movement. I have shown these gripping members as comprising two parts, 21 and 22, the former being curved to guide the stock in the manner contemplated by the 45 curved guide 7. The upper member 22 is capable of being raised and lowered to receive and release the stock through the instrumentality of a cam 23 acting on a lever 24 which is connected by a link 25 to a rock 50 shaft 26, upon which latter the upper member 22 is keyed. The shaft 26 and a second paralleling shaft 27, form the guides for the gripping members. The latter are designed to be reciprocated by a toothed sector 55 28 engaging teeth on the underside of gripping member 21, said sector being actuated by a cam 29. I have also shown the choke gage, bearing on the upper surface of the lower gripping member 21, in the form of 60 a lever 30, which is raised and lowered by means of a constantly-revolving cam 31. The gearing is outlined in Figs. 5 and 6.

The advantages of my present invention will be readily appreciated by those skilled 65 in the art. It will be seen that by means

thereof the advantage arising from feeding stock longitudinally and then transversely may be obtained without the necessity of locating the feeder to one side of the printing press or other paper-handling machine; that it is only necessary to partially remove the topmost article from the pile, that is to say, a sufficient distance to enable one end or portion thereof to project beyond the edge of the pile a sufficient distance to enable such projecting portion to be grasped by means for imparting to the article the secondary movement at right-angles to the initial movement. 70 75

I claim as my invention:

1. In a feeder, means for moving the topmost piece of stock from a pile thereof to cause a portion to project beyond the edge of such pile, and means for gripping the projecting portion of such topmost piece and moving the latter from the pile at right angles to its initial movement. 80

2. In a feeder, means for engaging the topmost article of a pile thereof and moving it longitudinally on the pile, and means for positively engaging the projected end of the article and then moving it from the pile at right-angles to its initial movement. 90

3. In a bag-tube feeder, means for engaging the topmost bag-tube of a pile thereof and moving it longitudinally on the pile, and means for then positively engaging the projected end of the bag tube and moving it from the pile at right-angles to its initial movement. 95

4. In a bag-tube feeder, means for engaging the topmost bag-tube of a pile thereof and moving it longitudinally to cause its opposite end to project beyond the edge of such pile, and means for gripping the projecting end of such topmost bag-tube and moving the latter from the pile at right angles to its initial movement. 100 105

5. In combination with a printing press, a bag-tube feeder located at one end thereof, means for engaging the topmost bag-tube of a pile thereof and moving it longitudinally on the pile, and means for positively engaging the projected end of said bag-tube and then moving it from the pile to the press at right angles to its initial movement. 110

6. In combination with a printing press, a feeder located at one end thereof, means for moving the topmost piece of stock from a pile thereof to cause a portion to project beyond the edge of such pile, and means for gripping the projecting portion of such topmost piece and moving the latter from the pile to the press at right angles to its initial movement. 115 120 125

7. In a feeder, means for moving the topmost piece of stock from a pile thereof to cause a portion to project beyond the edge of such pile, and gripping members for engaging such projecting portion and firmly 130

holding a substantial section thereof and for moving such topmost piece from the pile at right-angles to its initial movement.

8. In a feeder, means for moving the topmost piece of stock from a pile thereof to cause a portion to project beyond the edge of such pile, and revolving gripping members for engaging such projecting portion and firmly holding a substantial section thereof and for moving such topmost piece from the pile at right-angles to its initial movement.

9. In a feeder, means for moving the topmost piece of stock from a pile thereof to cause a portion to project beyond the edge of such pile, and co-operating revolving gripping members for engaging such projecting portion and firmly holding a substantial section thereof and for moving such topmost piece from the pile at right-angles to its initial movement.

10. In a feeder, means for moving the topmost piece of stock from a pile thereof to cause a portion to project beyond the edge of such pile, gripping members for engaging such portion and firmly holding a substantial section thereof, a choke gage interposed between the pile and said gripping members, and means for actuating the lat-

ter for moving such topmost piece from the pile at right-angles to its initial movement.

11. In a feeder, means for moving the topmost piece of stock from a pile thereof to cause a portion to project beyond the edge of such pile, gripping members for engaging such projecting portion and firmly holding a substantial section thereof, a reciprocating member adjacent to said gripping members for periodically engaging the pile to maintain the stock in place, and means for actuating said gripping members.

12. In a feeder, means for moving the topmost piece of stock from a pile thereof to cause a portion to project beyond the edge of such pile, gripping members for engaging such projecting portion comprising upper and lower rolls revoluble at right-angles to the initial movement of the stock, and feed-out rolls to which the stock is fed by said gripping rolls.

In testimony whereof, I have signed this specification in the presence of two subscribing witnesses.

CARL G. PRITCHARD.
